Primary Examiner—A. Hugo Word*Assistant Examiner*—Marcus Jackson*Attorney, Agent, or Firm*—Henri J. A. Charmasson; John D. Buchaca[57] **CLAIM**

The ornamental design for an identification tag for rolled documents, as shown and described.

DESCRIPTION

FIG. 1 is a perspective view of an identification tag for rolled documents showing my new design, with the broken line showing for illustrative purposes only and forming no part of the claimed design;

FIG. 2 is a front elevational view thereof;

FIG. 3 is a left side view thereof, the right side being a mirror image of the left side;

FIG. 4 is a rear elevational view thereof; and,

FIG. 5 is a bottom plan view thereof, with the top being a mirror image when the sign portion is rotated.

FIG. 5

FIG. 3

FIG. 4
